CLAIM

The ornamental design for a ball projector batting aid, as shown and described.

DESCRIPTION

FIG. 1 is a side elevation of a ball projector batting aid with a support member folded to a storage position showing my new design.

FIG. 2 is a top view of a ball projector batting aid with the support member folded to the storage position.

FIG. 3 is a bottom view of a ball projector batting aid with the support member folded to the storage position.

FIG. 4 is a right hand end view of a ball projector batting aid with the support member folded to the storage position.

FIG. 5 is a left hand end view of a ball projector batting aid with the support member folded to the storage position.

FIG. 6 is a side elevation of a ball projector batting aid with the support member extended in operative position.

FIG. 7 is a bottom view of a ball projector batting aid with the support member extended in operative position.
